US00D925597S

(12) **United States Design Patent** (10) Patent No.: **US D925,597 S**
Chandran et al. (45) Date of Patent: **** Jul. 20, 2021**

(54) DISPLAY SCREEN OR PORTION THEREOF WITH GRAPHICAL USER INTERFACE	D361,840 S	8/1995	Savage et al.
(71) Applicant: Masimo Corporation , Irvine, CA (US)	D362,063 S	9/1995	Savage et al.
(72) Inventors: Prashanth Rengaswamy Chandran , Irvine, CA (US); Anand Sampath , Irvine, CA (US); Keith Ward Indorf , Riverside, CA (US); Sebastian T. Frey , Laguna Niguel, CA (US); Bilal Muhsin , San Clemente, CA (US)	5,452,717 A	9/1995	Branigan et al.
	D363,120 S	10/1995	Savage et al.
	5,456,252 A	10/1995	Vari et al.
	5,479,934 A	1/1996	Imran
	5,482,036 A	1/1996	Diab et al.
	5,490,505 A	2/1996	Diab et al.
	5,494,043 A	2/1996	O'Sullivan et al.
	5,533,511 A	7/1996	Kaspary et al.
	5,534,851 A	7/1996	Russek
	5,561,275 A	10/1996	Savage et al.
	5,562,002 A	10/1996	Lalin
	5,590,649 A	1/1997	Caro et al.
	5,602,924 A	2/1997	Durand et al.
	5,632,272 A	5/1997	Diab et al.
	5,638,816 A	6/1997	Kiani-Azarbajayjany et al.
(**) Term: 15 Years	5,638,818 A	6/1997	Diab et al.
(21) Appl. No.: 29/624,391	5,645,440 A	7/1997	Tobler et al.
(22) Filed: Oct. 31, 2017	5,671,914 A	9/1997	Kalkhoran et al.
(51) LOC (13) Cl. 14-04	5,685,299 A	11/1997	Diab et al.
(52) U.S. Cl.	5,726,440 A	3/1998	Kalkhoran et al.
USPC ..... D14/489 ; D14/491	D393,830 S	4/1998	Tobler et al.
(58) Field of Classification Search	5,743,262 A	4/1998	Lepper, Jr. et al.
USPC D14/489, 491	5,747,806 A	5/1998	Khalil et al.
CPC A61B 5/14551; A61G 2205/50; G06F 3/04817; H04N 1/00424	5,750,994 A	5/1998	Schlager
See application file for complete search history.	5,758,644 A	6/1998	Diab et al.
(56) References Cited	5,760,910 A	6/1998	Lepper, Jr. et al.

CLAIM

The ornamental design for a display screen or portion thereof with graphical user interface, as shown and described.

DESCRIPTION

FIG. 1 is a front view of a display screen or portion thereof with graphical user interface showing our new design;
FIG. 2 is a front view of a display screen or portion thereof with graphical user interface in accordance with a second embodiment;
FIG. 3 is a front view of a display screen or portion thereof with graphical user interface in accordance with a third embodiment;
FIG. 4 is a front view of a display screen or portion thereof with graphical user interface in accordance with a fourth embodiment;

FIG. 5 is a front view of a display screen or portion thereof with graphical user interface in accordance with a fifth embodiment;

FIG. 6 is a front view of a display screen or portion thereof with graphical user interface in accordance with the first embodiment, shown in an alternate environment;

FIG. 7 is a front view of a display screen or portion thereof with graphical user interface in accordance with the first embodiment, with the claimed subject matter shown separately;

FIG. 8 is a front view of a display screen or portion thereof with graphical user interface in accordance with the second embodiment, with the claimed subject matter shown separately;

FIG. 9 is a front view of a display screen or portion thereof with graphical user interface in accordance with the third embodiment, with the claimed subject matter shown separately;

FIG. 10 is a front view of a display screen or portion thereof with graphical user interface in accordance with the fourth embodiment, with the claimed subject matter shown separately; and,

FIG. 11 is a front view of a display screen or portion thereof with graphical user interface in accordance with the fifth embodiment, with the claimed subject matter shown separately.

The broken lines showing a display screen or portion thereof, text and graphical elements form no part the claimed design.
